UNITED STATES PATENT OFFICE

WILLIAM FRIEDMAN, OF NEW YORK, N. Y., ASSIGNOR TO LUPE, INC., OF NEW YORK,
N. Y., A CORPORATION OF NEW YORK

CONTAINER

Application filed May 5, 1928. Serial No. 275,310.

This invention relates to containers and more particularly to loose powder vanity boxes for holding and dispensing a make-up material such as face powder, rouge and the like.

5 The primary objects of this invention are set forth in a co-pending application filed November 17, 1927 and bearing Serial No. 233,784. This invention relates to improvements in containers of the class described of 10 this co-pending application and particularly to an auxiliary means whereby the openings provided for the escape of loose powder may be positively closed when the container is not in use to prevent escape of powder from the 15 container. A still further object of the invention is to provide a container of the class described in the above mentioned co-pending application wherein the openings providing for the escape of loose powder are formed 20 of considerable width to more readily permit the escape of powder therethrough.

With these and many other objects in view which will more readily appear as the nature 25 of this invention is better understood, the same consists in the novel construction, combination and arrangement of parts set forth in the accompanying drawings, in which;

Figure 1 is a plan view of a loose powder 30 container constructed in accordance with my invention showing the same in open position to more clearly reveal the nature of the same;

Figure 2 is a sectional view thereof taken on the line 2-2 of Fig. 1.

35 In the above mentioned views similar characters of reference are employed to designate similar parts throughout and the improved container involves in its general organization an outer cover 2 which serves to close the usual opening 3 of the box. This box is adapted to be not only closed by outside cover 2, but also by an inner cover 4 which is termed throughout this specification as a dispensing retainer. The novel construction of this dispensing retainer 4 constitutes a major part 40 of the present invention. Both the cover 2 and the dispensing retainer 4 are hinged as at 5 and 6 respectively to the body 1 of the box so that one may be opened independently of 45 the other. Each of these covers has suitable

55 snap fastening means as is the usual case for retaining it releasably in closed position. The dispensing retainer 4 is intended to be opened to permit access to the interior of the box for the purpose of inspecting or filling the same.

56 The dispensing retainer 4 is so constructed that it is normally closed to prevent escape or spilling of the powder in the box. However, means are provided to permit the escape 60 of a limited amount of powder when a puff or the like is rubbed over the same or when the same is gently tapped. However, as soon as pressure is removed from the dispensing retainer the same occupies its normal position 65 to prevent the escape of powder. Various ways may be provided for accomplishing this action, one has been illustrated in the above mentioned co-pending application but the present invention treats of an improved 70 method whereby this dispensing action may be obtained.

75 As clearly shown, the dispensing retainer 4 is comprised of a pair of superimposed plates 7 and 8. These plates may be formed in any suitable manner and of any suitable material. For instance, I may make the device of cardboard, but for the usual type it is preferable to form the same of resilient metal 80 stampings on account of the cheapness, lightness and strength of the latter. Irrespective of these views of manufacture the essential features of the invention are always preserved. The plate 7 is stamped or cut between a continuous rim 20 and an integral center piece 21, into two or more segments 22 85 which are slightly spaced from each other to provide openings whereby the powder may escape from the interior of the box. The material is essentially sufficiently resilient to normally retain the segments in the plane of the outer margin or rim 20 and of the center piece 21 so that the plate will provide a substantially smooth surface under normal conditions.

90 Underlying the plate 7 I preferably provide a second or feeder plate 8, the construction of which may be varied to considerable extent. Since I provide positive openings between the segments, the lower plate 8 is ar- 95 100

ranged to function as a closure for the said openings, and also functions as a feeder, that is, retains a quantity of powder between said plate 8 and plate 7 ready to issue from the said opening when desired. In the specific construction shown herein the lower plate 8 is imperforate, as a result of which, when the dispensing retainer is depressed, powder will be drawn into the space between the two plates. This is due to a current of air being set up by depression of the lower plate which finds an exit through the perforations of the upper plate.

As clearly shown the outer rim 20 and the center piece 21 are connected by means of irregularly shaped segments 22 formed by virtue of the fact that the face of the plate is formed with a plurality of straight narrow slots.

From the foregoing it is thought that the construction and use and many advantages of the herein described container will be apparent and it will also be understood that changes in the form, proportion and minor detail in construction may be resorted to without departing from the spirit of the invention or sacrificing any of the advantages thereof.

Having thus described my invention, I claim:

1. A device for dispensing powdered substances comprising a resilient plate; there being a plurality of crevices formed in said plate enabling the plate to be depressed; means normally closing said crevices to prevent the escape of powder therethrough and actuated by depression of said plate for opening said crevices to permit a limited quantity of powder to pass through the same.

2. A device for dispensing powdered substances comprising a resilient plate there being a plurality of crevices formed in said plate enabling the plate to be depressed; means normally covering said crevices to prevent the escape of powder therethrough said means permitting the crevices to be uncovered when said plate is depressed to permit a limited amount of powder to pass through the same.

3. A device for dispensing powdered substances comprising a resilient plate; said plate having a plurality of resilient portions formed therein; said portions being spaced to provide crevices therebetween; a second plate secured to said first mentioned plate and normally closing said crevices whereby depression of said first mentioned plate will uncover said crevices to permit a limited amount of powder to escape therethrough.

4. A device of the character described comprising a resilient plate there being a plurality of crevices formed in said plate enabling the plate to be depressed; a second and imperforate plate secured to said first mentioned plate and normally closing said crevices to prevent the escape of a material

therethrough, depression of said plates causing said imperforate plate to uncover said crevices to permit the escape of a limited amount of material therethrough.

5. A device characterized by a resilient closure member having a plurality of criss-cross crevices therein enabling the closure to be depressed for dispensing powder therethrough by manipulation of said member.

6. A device characterized by a resilient closure member having a plurality of criss-cross crevices therein enabling the closure to be depressed for dispensing powder therethrough, and means cooperating with said resilient closure for assisting in discharge of powder from said crevices upon manipulation of said member.

7. A device characterized by a resilient closure member having a plurality of irregularly arranged crevices cooperating to permit depression of said member for obtaining passage of powder through said irregularly arranged crevices by manipulation of said member.

8. A device characterized by a resilient closure member having a plurality of straight line crevices cooperating to permit depression of said member for obtaining passage of powder through said crevices by manipulation of said member.

9. A device characterized by a resilient closure member having a plurality of irregularly arranged straight line crevices cooperating to permit depression of said member for obtaining passage of powder through said irregularly arranged crevices by manipulation of said member.

10. A device characterized by a resilient closure member having a plurality of irregularly arranged crevices cooperating to permit depression of said member for obtaining passage of powder through said irregularly arranged crevices, and a second member cooperating with said resilient closure for assisting in discharge of powder from said crevices upon manipulation of said member.

11. A device characterized by a resilient closure member having a plurality of irregularly arranged crevices cooperating to permit depression of said member for obtaining passage of powder through said irregularly arranged crevices, and a second member secured to the first said member so as to normally lie contiguous thereto and having portions free to separate from the first mentioned member for assisting in discharge of powder from said crevices upon manipulation of said members.

12. A device characterized by a resilient closure member having a plurality of irregularly arranged straight line crevices cooperating to permit depression of said member for obtaining passage of powder through said irregularly arranged straight line crevices, and a second member secured to the first said

member so as to normally lie contiguous thereto and having portions free to separate from the first mentioned member for assisting in discharge of powder from said crevices
5 upon manipulation of said members.

13. A device characterized by a closure having separable parts both of which are movable, and between which powder may pass from below said closure to escape above
10 said closure by passing between said parts.

14. A device characterized by a closure having separable parts one of which is resilient and between which powder may pass, some of the powder adapted to lodge between
15 said parts ready to escape above said closure upon separating said parts.

15. A device characterized by a main powder chamber, a closure for said chamber having parts forming an auxiliary powder retaining means therebetween, one of said parts being resilient and perforate, some of the powder adapted to lodge in said auxiliary powder retaining means ready to escape above said closure upon separating said parts.
